ELEVATOR CONTROL SYSTEM

Ernest L. Gale, Yonkers, N. Y., assignor, by mesne assignments, to The Gurney Elevator Co., Honesdale, Pa., a corporation of Pennsylvania

Application November 30, 1927, Serial No. 236,740

50 Claims. (Cl. 187—29)

This invention relates to a push button control system for elevators.

The objects of the invention reside in various provisions summarized as follows:

- 5 First, a push button control system having combined dispatch and intercepting functions and arranged for multi-speed elevators, the control means, i. e., push buttons and their associated floor-relay switches, being operable collectively, 10 or in other words, at any time regardless of the position of the car and the direction of car movement and effective to intercept the car by effecting its slow-down and stop, at the landings successively in their natural order regardless of the 15 order in which the push buttons are actuated, the car for any one direction of movement completing its trip to a farthest landing for which a push button is actuated before reversal of car movement is normally effective:
- 20 Second, a push button control system for multi-speed elevators comprising for each of a plurality of landings, "up" and "down" push buttons located at the landings and on the car, having combined dispatch and intercepting functions:
- 25 Third, means for rendering the system effective for dispatch of the car in the event of the car gate being left in open position by the last passenger to leave the car:
- 30 Fourth, means automatically to return the car to a selected landing or "home" station:
- 35 Fifth, a time-limit switch to control duration of each car stop, effective at the expiration of a predetermined period of time, provided the car gate and the hoistway doors are closed but regardless as to whether they are opened during the stopping period to continue movement of the car in the same direction as when intercepted, or in a reverse direction as in the event if the car has completed its trip in response to a farthest 40 actuated push button:
- 45 Sixth, a push button control system arranged so that any actuated "up" push button, or any farthest-up actuated "down" push button if for a landing above that for which a farthest-up "up" button is actuated, if actuated while the car is moving downwardly from its landing, will after the car completes its downward trip in response to any actuated button farthest-down, condition the system for reverse car movement so that the act of closing the car gate and the hoistway door at such farthest-down landing, or the operation of the time-limit switch, will initiate movement of the car upwardly. During movement of the car upwardly, only "up" push 50 buttons at the intermediate landings are effective to intercept the car and it is automatically slowed down and stopped at the landing farthest-up for which a push button is actuated regardless as to whether such push button is an "up" or a "down" push button:
- 55 Seventh, a push button control system arranged so that any actuated "down" push button, or any farthest-down actuated "up" push button if for a landing below that for which a farthest-down "down" push button is actuated, if actuated during movement of the car upwardly away from its landing, will, after the car completes its upward trip in response to any actuated push button farthest-up, condition the system for reverse car movement so that the act of closing the car gate, 15 and the hoistway door at such farthest-up landing, or the operation of the time-limit switch, will initiate movement of the car downwardly. During such downward movement of the car, only "down" push buttons at the intermediate landings are effective to intercept it and it is automatically slowed down and stopped at the landing farthest-down for which a push button is actuated regardless as to whether such push button is an "up" or a "down" push button:
- 20 Eighth, a dual control system whereby the push button system alone functions as herein-before suggested, and for car switch control, the car switch is operable independently of the push buttons to establish direction for car movement and effect car start, slow-down, stop and reversal at will at any point intermediate the limits of car travel but at the same time the car and hall push buttons remain operable only to intercept the car. The car switch can remain in "on" or running position until reversal of car movement is desired and at the same time the car is intercepted, or in other words, automatically slowed down and stopped in response to actuated car and hall push buttons. Start of the car from each landing at which it is intercepted is effected by closing the landing door and the car gate or by the operation of the time-limit switch:
- 25 Briefly stated, a system of control as herein provided having "up" and "down" push buttons for each intermediate landing, located at the landings and on the car, is so arranged that according to one mode of operation thereof, a hall passenger needs only to momentarily actuate a hall push button once which corresponds to direction in which it is desired to travel, and, assuming the car is not being used, such button, regardless as to whether it is an "up" or a "down" push button, will initiate movement of the car toward its landing from a position above or below the latter.

- Either the "up" or the "down" push button will stop movement of the car which it initiates, on first approach of the car toward its landing from either direction conditional on the assumption that
- 5 none of the push buttons for a landing or landings beyond and toward which the car is moving, is actuated subsequently to said initiating push button being actuated, and prior to car arrival at the landing corresponding to said initiating push
- 10 button. However, if car movement and the push button which initiates it, correspond as to direction, such push button will stop the car at its landing on first approach thereto unconditionally. If car movement and the push button which initiates it do not correspond as to direction, such push button is ineffective to stop movement of the car at its landing on first approach thereto if during said movement a push button at a landing or landings beyond and toward which the car is moving is actuated, however, said initiating push button, by the single actuation thereof, conditions the system so that when the car completes its trip in response to the farthest actuated push button for the landing beyond, direction is
- 15 established for reverse movement of the car and the act of closing the car gate and the hoistway door, or the operation of the time-limit switch initiates movement of the car in reverse direction to return it to the landing corresponding to the initiating push button, and the latter is effective automatically to cause slow-down and stop of the car during its return movement.
- In the accompanying drawings, Figs. 1A and 1B illustrate in a more or less diagrammatic manner, 35 a push button control system of the intercepting type arranged for a multi-speed elevator having for each of a plurality of landings, "up" and "down" push buttons at the landings and on the car;
- 40 Fig. 2 illustrates diagrammatically and in part, a push button control system of the intercepting type arranged for a multi-speed elevator and having a single push button at each of the landings and corresponding push buttons on the car;
- 45 Fig. 3 is an end elevation of a remote controller of a standard and well known type slightly modified to adapt it for use with the present arrangement of circuits; and
- 50 Fig. 4 illustrates diagrammatically, a modified form of control apparatus together with certain circuits which form a part of an intercepting push button control system for a multi-speed elevator system of the two button type.
- Referring now more particularly to Figs. 1A and 1B, the invention comprises an elevator car C adapted for operation by a hoisting motor M through the intermediary of any well known type of gearing or roping (not shown). So far as the present invention is concerned, the hoisting motor may be of any well known type adapted for multi-speed regulation such, for example, as may be obtained by operating it by a Ward-Leonard system or what is commonly known in the art as a variable-voltage system, or a multi-voyage system, or a rheostat method of control which involves varying the strength of a shunt field winding A of the hoisting motor, the latter method being illustrated herein. Any method for obtaining speed regulation involves the use of a fast and slow speed switch designated J. Other elements which comprise the present system are as follows:—an electromagnetically operable speed change switch B; an accelerating switch E to control a sectional starting resistance F for the motor M, a
- car switch G; a change-over switch H by means of which the dispatch function or start of the car in one direction or the other as controlled by the push button controlled circuits is transferred to the car switch; electro-magnetically operable reversing switches R, R', to control the hoisting motor to move the car upwardly and downwardly respectively; "up" and "down" direction switches D and D' respectively, the former having contactors 1 to control an energizing circuit for a winding 2 of the "up" reversing switch, and the latter having contactors 3 to control an energizing circuit for a winding 4 of the "down" reversing switch. An intercepting slow-down circuit 5 for an operating winding 6 for the speed-change switch B is rendered effective for movement of the car upwardly by contactors 7 of the "up" direction switch D; an intercepting slow-down circuit 8 for said winding 6 is rendered effective for movement of the car downwardly by contactors 9 of the "down" direction switch D'. Car gate contactors, hoistway door contactors, an emergency stop switch, a cam releasing magnet to control door locks (not shown) are designated 10, 11, 12 and 13 respectively. A car gate 14 is provided with a gate closer comprising a lever 15 actuatable by a spring 16. A latch mechanism consisting of a latch 17 on the car gate cooperating with a toothed rack 18 is arranged to hold the car gate open, the rack 18 being actuated by an electro-responsive device 19, to release the latch to render the spring 16 and lever 15 effective to close the gate.
- The system comprises further, "up" and "down" hall push buttons 20 and 21 respectively for each landing intermediate the end landings and one button for each end landing. The car is provided with "up" and "down" push buttons corresponding in number to the hall push buttons and designated 23A and 21A.
- "Up" and "down" floor-relay switches 22 and 23 respectively for each of the intermediate landings and one for each end landing are of a well known or standard type, each having a winding 24 energizable by momentary actuation of its associated push button. These switches are maintained in actuated position electrically, or in other words, are made self-holding by providing for each winding a self-holding circuit 25 which feeds said windings in parallel by way of their associated self-holding contactors 26. The initial energizing circuit as controlled by a push button and also the self-holding circuit for the "up" floor-relay windings, includes contactors 27 of relays 28, one of which is associated with each "up" floor-relay switch.
- Similar circuits for the "down" floor-relay windings include contactors 29 of relays 30, one of which is associated with each "down" floor-relay switch. The contactors 27 and 29 are normally closed and since the only normal opening or break in the energizing circuit for any floor-relay switch winding is at its associated push button, this means that the push buttons are actuatable at any time, singly or collectively, regardless of the position of the car and the direction of movement of the car, to energize their associated floor-relay windings. The contactors 27 and 29 through their control of the self-holding circuits, function to maintain their associated floor-relay switches when actuated in closed position until the car responds thereto by stopping at their landings. Hence, this arrangement in effect requires any button to be actuated but once in order to effect response of the car there-

to, regardless of the position of the car and the direction of movement of the car, when the button is actuated. These relays 28 and 30 are in effect what may be termed de-energizing relays 5 and their windings 31 and 32 respectively form two sets, each rendered effective independently in accordance with direction of car movement. Therefore, for movement of the car upwardly, windings 31 corresponding to landings stopped 10 at are momentarily energized to open their contactors 27 to deenergize only "up" floor-relay windings corresponding to landings stopped at. Likewise, for movement of the car downwardly windings 32 corresponding to landing stopped at 15 are momentarily energized to open their contactors 29 to deenergize only "down" floor-relay windings corresponding to landings stopped at. The circuit-controlling apparatus for the windings 31 and 32 comprises as a whole two sets of 20 circuit-controllers, one effective for movement of the car upwardly and the other effective for movement of the car downwardly. This circuit-controlling mechanism is of the normally open-circuited type consisting of feed-contactors 33 25 and 34 actuatable in accordance with car position, momentarily to engage fixed contactors 35 and 36 respectively for each of the intermediate landings. When the car is at any one of the landings, contactors 33 and 34 electrically engage contactors 35 and 36 of the corresponding landing, 30 said contactors being disengaged by movement of the car therefrom. A feed wire 55 connects the feed-contactors 33 in parallel and includes the back contactors 56 of the "down" direction switch D', and a feed wire 111 connects the feed-contactors 34 in parallel and includes the back contactors 58 of the "up" direction switch D. The direction switches are closable only one at a 35 time and hence by controlling the feed wires 55 and 111 through the agency of their back contactors, only one set of relays 28 or 29 is rendered effective at a time which in effect means that for movement of the car upwardly only "up" floor-relay windings will be de-energized 40 corresponding to landings stopped at excepting when a farthest-up point of dispatch is reached, in which case either one or both will be de-energized, and for movement of the car downwardly only "down" floor-relay windings will be de-energized 45 corresponding to landings stopped at excepting when a farthest-down point of dispatch is reached, in which case either one or both will be de-energized. With this arrangement, the effect will be such that each push button upon 50 completing its function to cause stop of the car at its landing, will as the car moves away from its landing, be rendered operable again to energize its associated floor relay winding.

Car controlled floor-selector mechanism to 55 control intercepting automatic slow-down circuits and also directional circuits, is illustrated herein as being of a type located in the hoistway to be actuated by a cam on the car. However, the floor-selector mechanism may be of the well known type slightly modified, as illustrated 60 in Fig. 3 located remotely from the car and actuated thereby directly by any of the well known types of drive such as a cable and drum, reel and tape or the sprocket and chain type (not shown).

The floor-selector mechanism for each of the 65 intermediate landings consists of a pivoted switch arm 37 carrying a segmental contactor 38 to cooperate with fixed contactors 39 and 40 to control a feed for the "up" direction switch winding, and to cooperate with contactors 39 and 41 70 to control a feed for the "down" direction switch winding. A pair of additional segmental contactors 42 and 43 are also carried by the switch arm, the former to cooperate with fixed contactors 44, 45 and 46 to control the "up" intercepting circuit which effects automatic slow-down of the car when it is moving upwardly and the latter to cooperate with fixed contactors 47, 48 and 49 to control the "down" intercepting circuit which effects automatic slow-down of the car when it is moving downwardly.

The circuit-controlling mechanism comprising the contactors 33 and 34 controllable in accordance with car position together with the associated fixed contactors 35 and 36 may be in the form of a unitary structure of itself located 15 remotely from the car in which case there would be only one movable contactor 33 for "up" direction and one movable contactor 34 for "down" direction, said two contactors having either an oscillating movement as effective by mounting them on a threaded shaft or worm driven from the car, or being mounted on a rotatable member, such, for example, as a car driven shaft 160 of a remote controller illustrated in Fig. 3, said 20 shaft carrying usual rocker arms 161 which actuate the switch mechanism of the remote controller in a well known manner. As illustrated in Fig. 1B, the contactors 33 and 34 are carried by the pivoted switch arm 37 for each intermediate landing and only one contactor is provided for the end landings, normally out of engagement with their fixed contactors 35 and 36 so that movement of the switch arm 37 from one position to another position causes the contactors 33 and 34 to momentarily engage their associated fixed contactors when the car is at a landing and to disengage same when the car moves away from the landing.

The floor-relay switches for each intermediate landing comprise "up" and "down" contactors 59 and 51 respectively which together with floor-selector switch contactors 38, 39 and 40 control dispatch operation or, in other words, initiate start of the car in response to actuated 40 hall or car push buttons, through control of the "up" and "down" direction switches which are closable one at a time to close their top contactors. Both the "up" and "down" car-start contactors 59 and 51 for any one landing are 45 connected in parallel by a wire 52 connecting with the common feed contactor 39 on the floor-selector switch.

The floor-selector switches are actuated in a well known manner so that when the car moves 55 downwardly it sets the segments 38 to close-circuit contactors 39 and 40. A common return wire 53 provides a feed for the "up" direction switch winding and connects the "up" floor-selector contacts 40 in parallel. As the car moves 60 upwardly it sets the segments 38 to close-circuit contactors 39 and 41. The contactors 41 of all the floor-selectors are connected in parallel by a common return wire 54 for the "down" direction switch winding. Since the push button 65 controlled car-start or dispatch contactors 50 and 51 for each intermediate landing are connected in parallel by the common wire 52 connecting with the common feed contactor 39 of the floor-selector switch, either the "up" or the 70 "down" push button for each landing above car position is rendered effective to control the "up" reversing switch, and either the "up" or "down" push button for each landing below car position is rendered effective to control the "down" re- 75

versing switch. This arrangement in effect provides means whereby a hall passenger needs only to press the hall push button corresponding to the direction in which it is desired to travel, and 5 if the car is not in use, such push button regardless of whether it is an "up" or a "down" push button, will originate movement of the car toward its landing from a position either above or below it as determined by the setting of its 10 associated segment 38 and effect slow-down and stop of the car at its landing from either direction on first approach thereto conditionally, but only so if said initiating button does not correspond to car movement which it initiates, or 15 on second approach unconditionally.

A feed circuit 83 for the reversing switch windings constitutes an independent or complete circuit by itself and is controlled by the aforesaid push button controlled car-start circuits through their control of the direction switches to initiate car movement in one direction or the other.

Two stop switches S and S' are provided on the car, the switch S to control all stops for movement of the car upwardly and the switch S' to control all stops for movement of the car downwardly. The switches are actuatable to open-circuit their associated stop contactors by co-action with cams T, T' fixed in the hoistway, there 20 being an "up" and "down" cam adjacent each intermediate landing and one cam at each end landing. The "up" and "down" cams form two independent sets positioned in independent vertical planes and by coaction 25 with their associated stop switches open their contactors only momentarily as the car approaches a landing. Each stop switch is mechanically maintained in inoperative position with its contactors closed, by means of a spring W, so 30 that the switch rollers will not strike cams at floors which are not stopped at. However, when slow-down is effected one or the other of the stop switches is movable by energization of an electro-responsive device 115 to operative position 35 so that its roller is in position to cooperate with its stop cam. During such movement of the switch to said operative position and until it is actuated by the cam, its contactors are maintained closed by a relatively light spring x to 40 maintain the energizing circuit for a reversing switch winding closed uninterruptedly. When stop is effected, said stop switch is mechanically returned to normal or inoperative position by a spring W, so that when the car is at the landing, 45 the roller is retracted and the contactors are closed.

Hence, according to the mode of operation of the stop switches as constructed and arranged herein, they are maintained in retractive position 50 mechanically and at the same time their contactors are closed, and they are actuatable by electro-responsive means to an operative position or, in other words, a cooperative position with respect to their cams, independently in accordance with 55 direction of car movement.

To intercept the car by effecting its automatic slow-down, two sets of circuits are provided, one set to intercept the car through the agency of the speed-change switch B in response to actuated "up" push buttons, and the other set arranged to intercept the car through the agency of switch B in response to actuated "down" push buttons. The set of intercepting circuits to effect 60 automatic slow-down for movement of the car upwardly, consists of the wire 5 connecting with

a plus main by wires 59 and 60 and includes all the back contactors 61 of the "up" floor-relay switches in series and connects with one of the terminals of the speed-change winding 6 after passing through the "up" direction switch contactors 7. This series circuit, as will be evident, is susceptible of being open-circuited at any time at any of the back contactors 61 by actuation of their associated floor-relays as effected by actuation of their associated "up" push buttons. However, another independent circuit is completed for the winding 6 by way of wire 5' and includes all the floor-selector switch contactors 42, 44 and 45 in series for one position of the selector switch, or contactors 42, 45 and 46 in series for the other position of the selector switch. The contactors 44 and 46 of each switch are connected in parallel, so that for either of the two positions in which a selector switch is set by movement of the car, it closes the series circuit at that point but this circuit is opened only momentarily by movement of the contactor 42 from one position to the other. This series circuit or wire 5' forms a shunt around all of the back contactors 61, it branching from the wire 60 at a junction 62, and after shunting around all of said contactors 61 by way of the floor-selectors, it again forms a junction at 62' with the wire 5. The series wire 5' provides an energizing circuit for the winding 6 independently of the series wire 5, and is open-circuited at only one point at a time or, in other words, only at a floor-selector switch when actuated by the car movement. The selector switches are constructed and arranged to break the circuit or wire 5' only momentarily and to quickly reclose it so that in effect each break in the wire 5' is of relatively short duration as for example is obtained by a snap switch action. This operation of the floor-selectors acts quickly to re-close the wire 5' to complete the energizing circuit for the winding 6, effectively prevents slow-down of the car when the latter is moving upwardly from being initiated by actuation of any push button after the car has passed the slow-down point corresponding to such a button. With the car at any landing, the series circuit 5' is completed by way of the floor-selector contactors independently of the shunt circuits. However, it will be understood that any "up" push button actuated at such time is effective to energize its floor-relay winding and the latter will be maintained energized to maintain its floor-relay switch in actuated position until the car responds thereto by stopping at its landing, so that in effect it is required to actuate any button only once in order to effect response thereto. Such momentary opening and re-closing of the circuit 5' by means of a standard hoistway type of floor-selector switch mechanism is obtained by so positioning the contactor 46 that by movement of the car upwardly, the segmental contactor 42 will be caused to engage it immediately after disengaging the contactor 44 so that the energizing circuit 5' is then re-closed at the contactors 45, 42 and 41. As will be evident, the circuit 5' will be closed at a floor-selector switch when in either set position as effected by movement of the car upwardly and downwardly. The set of circuits 5 and 5' will be understood, control the slow-down of the car only when it is moving upwardly and are rendered operable by closing the wire 5 at the contactors 7 of the "up" direction switch D. The back contactors 61 of each of the up floor-relay switches control a shunt circuit around said contactors including their respective select-

switch contactors 42, 44, 45 by way of parallel wires 63 which cross-connect the two series wires 5 and 5'.

Hence, when the car is moving upwardly it will 5 not be slowed down at landings for which "up" push buttons are not actuated because in such case their associated contactors 61 shunt current from wire 5' around their respective floor-selectors as each is actuated momentarily to open 10 said wire 5'. In this manner, the winding 6 is maintained energized and car movement at fast speed rate will not be interrupted at such landings.

However, when the car is moving upwardly it 15 will be automatically slowed down when approaching landings for which "up" push buttons have been actuated because in such case contactors 61 which correspond to the actuated "up" push buttons are opened, thereby opening the 20 shunt around their associated floor-selectors.

Therefore, the winding 6 will be de-energized 25 to effect automatic slow-down as each floor-selector whose shunt is open, is actuated by the car momentarily to open-circuit the series wire 5'. Two wires 8, 8' controllable respectively by 30 back contactors 61' of the "down" floor-relays and floor-selector switch contactors 43, 47, 48 and 49, together with shunt wires 63' form a set of circuits rendered effective by contacts 9 35 of the "down" direction switch D', to intercept the car by effecting its automatic slow-down in response to actuated "down" push buttons, through control of the speed-change switch winding 6. For downward movement of the car, 40 this set of circuits is controlled at the "down" floor-relay switch contactors 61' and the floor-selector contactors in the same manner as has been described for the set which functions to intercept the car when it is moving upwardly. 45 This being so, a detailed description of the "down" set of intercepting slow-down circuits and the arrangement of the contactor mechanism to control same is unnecessary, it being necessary only to point out that the two sets of intercepting circuits are rendered effective independently in accordance with "up" and "down" direction of car movement as determined by whatever direction switch is in closed position.

A floor-selector of the well known remote type 50 modified somewhat in a manner as illustrated in Fig. 3, provides for momentarily opening and again re-closing both sets of intercepting circuits and also embodies contact mechanism arranged to control the direction switch winding circuits, 55 the contact mechanism and so forth as illustrated constituting the arrangement for any one intermediate landing. Contactors 140 control the "up" intercepting circuit 5' and contactors 141 control the "down" intercepting circuit 8'. Each 60 set of contactors comprises a fixed contact finger to coat with a contactor carried by a usual rocker arm 142. Secured to the lateral face of the contact finger is an insulator 143 having beveled ends and operating by a camming action to cause 65 the finger and stem to be electrically disengaged when the rocker arm is rocked in the usual manner by movement of the car. Hence, when movement of the car is upwardly, the intercepting circuit 5' as controlled by each set 70 of contactors 140, is open-circuited only momentarily when the contactor on the rocker arm engages the insulator on the contactor finger, and is re-closed by the contactor on the rocker arm engaging the contact finger at a point below 75 the insulator. The contactors 141 are of the

same construction and for movement of the car downwardly have a mode of operation the same as just described for the contactors 140.

Two sets of contactors 144 and 145 are adapted 5 to control the circuits for the "up" and "down" direction switch windings, each set comprising a contact finger fixed in position for coaction with its associated contactor carried by the rocker arm. It will be seen from the description and drawings that for any intermediate landing, the 10 contact mechanism and so forth therefor as arranged on a remote controller consists of the two rocker arms 142, 142', each carrying two movable contactors to coat with associated contact fingers, and that the contact mechanism 15 which controls the intercepting wires 5' and 8' for "up" and "down" movement of the car is constructed and arranged to be open-circuited only momentarily.

Coming now to a detailed description of the 20 operation of the parts, a hall passenger needs only to actuate an "up" or a "down" hall push button according to the direction in which it is desired to travel. Momentary actuation of either of said buttons, at any landing will when the car is not 25 already in use, bring the car to that landing from its position whether above or below same and effect its slow-down and stop at that landing. Assume now, for example, that the car is not in use and is at rest at the first landing with all 30 the hoistway doors and car gate closed. For such condition, the various elements will assume positions illustrated. A passenger at the third landing desires to go down and accordingly actuates the "down" button thereat. By momentarily 35 actuating said button an energizing circuit is completed for the winding 24 of the third landing "down" relay switch 22, causing the operation of the latter to open its back contactors 61' and close its two sets of top contactors 51 and 26. 40 This operation of the floor-relay switch will in effect cause energization of the "up" direction switch winding 64A, by completing its circuit at the contactors 51; the contactors 26 complete a self-holding energizing circuit for the floor-relay 45 switch winding 24; and opening of the back contactors 61' opens the shunt around the third landing floor-selector contactors which control the series energizing circuit 8' for the winding 6 of the speed-change switch. The "up" direction 50 switch will now operate to close its top contactors 1, 7 and 101, and open its back contactors 58 and 112. The energizing circuit 5' for the winding 6 is now completed at the contactors 1 and the speed-change switch B will operate to close its 55 contactors 64 and 65 and to open its back contactors 66. An energizing circuit for the "up" reversing switch winding 2 is now completed by the closing of the direction switch contactors 1 and the speed-change switch contactors 64, to 60 cause the "up" reversing switch R to close and at the same time, cause the brake to release. The motor M will now operate to move the car upwardly. The brake and motor circuits are old and well known and, therefore, are not traced in detail herein. The accelerating switch E operates in a well known manner to control the starting resistance, and when its last arm closes, it closes the contactors 67. An energizing circuit 65 for winding 68 of the fast and slow speed switch J branches from the reversing switch winding circuit at a junction 83' and includes the contactors 65 and 67, in series so that with both sets of said contactors closed, said circuit is completed 70 to effect operation of the switch J to open-circuit 75

contactors 69 and thus open the short-circuit around a resistor 70 in the circuit of the shunt field winding A of the hoisting motor and cause operation of the hoisting motor to move the car at fast speed rate.

The push button circuit may be traced as follows: wire 59 connecting with the plus main, through "down" button 21 at the third landing, wire 71, relay switch winding 24 to wire 72, contactors 29 of the de-energizing relay 30, wires 73, 74 and thence to the minus main by wire 75.

The self-holding circuit for the third landing "down" floor-relay switch may be traced as follows: the positive self-holding feed wire 25, wire 76 forming a junction at 76' with wire 25, self-holding contactors 26, wire 71 forming a junction with wire 71 at 71', thence through relay winding 24 to the minus line by way of the circuits as traced above.

The energizing circuit for the winding 64A of the "up" direction switch may be traced as follows: from wire 59, wire 78, contactors 51, wire 52 which connects "up" and "down" contactors 50 and 51 in parallel, through the third landing floor-selector switch by way of the contactor 39, segment 38 and contactor 40, wire 79 which forms a junction at 79' with the common feed wire 53 which includes the change-over switch H and connects by wire 136 with one of the terminals of the winding 64A of the "up" direction switch D, through said winding to back-contactors 81 of the "down" direction switch D', and thence by way of wire 82 to the minus main, said wire including back-contactors 195 of the "down" reversing switch.

The energizing circuit for the winding 2 of the "up" reversing switch may be traced as follows: wire 59, wire 83 including the car gate contactors 10, contactors 84 controlled by the car gate rack 18, and emergency stop switch 12, through speed change switch contactors 64, to wire 85, direction switch contactors 1, wire 86, through the winding 2 of the "up" reversing switch, wire 87, back-contactors 88 of the "down" reversing switch, and thence to the minus main by wire 89 which includes the normally closed contactors 90 and 91 of the "up" and "down" stop switches respectively in series.

With the "up" reversing switch in closed position, it completes at its contactors 110 a self-holding circuit for its winding 2, controlled by the stop switch contactors 90 and 91, said circuit receiving its feed independently of the contactors 64 which are in the initial energizing circuit for said winding and including contactors 106 of switch H. This self-holding circuit may be traced as follows: the same as heretofore traced to a junction 103 with wire 83, contactors 106, wire 104, thence through contactors 110 to wire 105 which forms a junction with wire 86, thence through the winding 2 and from there on to the minus main by way of wires 87, 89 which include back-contactors 88, and stop switch contactors 91 and 90 in series.

The door-lock cam releasing magnet 13 and the operating winding 19 for the gate releasing rack 18 are connected in parallel by wires 92 and 93 respectively fed from wire 94 by way of contactors 101 of whichever direction switch is closed, the wire 93 being subject to the effect of hoistway door contactors 11. These parallel wires form a junction at 95 with a wire 96 which connects with the minus main and includes normally closed contactors 97 of a timing switch 98 so rendered by providing it with a dash pot 99. The

timing switch also controls normally closed contactors 100 in the circuit of the winding 6. With this arrangement of circuits, the winding 19 cannot be energized to unlock the car-gate to permit its closure unless all the hoistway doors are closed and locked, thus there is no danger of the closure of the gate being initiated while a passenger is stepping onto or off of the car. Furthermore, since the contactors 84 are in the feed circuit of the reversing switch windings, it is necessary for all hoistway doors to be in closed and locked position before the car can be started. This is so because the closing of the contactors 84 is dependent on energization of the winding 19 and the circuit for the latter can be closed only when all the hoistway doors are closed and locked.

The intercepting circuit for the winding 6 of the switch B may be traced as follows: from wire 59, wire 60, wire 5' branching from wire 60 at the junction 62, the wire 5' including the floor-selector contactors 42, 44 and 45 for all landings (excepting the lower end landing) in series, and forming a junction at 62' with the wire 5 which extends by way of direction switch contactors 1 and contactors 100 of the timing switch 98, through the winding 6 to the minus main.

The circuit for the winding 68 of the fast and slow speed switch may be traced as follows: the same as for the reversing switch winding up to the junction 83' and branching therefrom to wire 138 which includes contactors 138' of the change-over switch H, contactors 65 to wire 107, contactors 67, wire 108, through the winding 68 and by wire 109 to the minus main.

The feed wire 55 for the "up" de-energizing relay windings 31 is now closed at the back-contactors 56 of the down direction switch which in effect means that only "up" de-energizing contactors 33 and 35 are rendered effective and a wire 106A common to the windings 31 connects with the minus main and includes the back-contactors 123 in series of both the "up" and "down" reversing switches so that in effect only the windings of the "up" floor relays which correspond to landings stopped at are de-energized when movement of the car is in an upward direction. The "down" de-energizing contactors 34 and 36 are rendered ineffective by reason of the feed wire 111 being open-circuited at the "up" direction switch contactors 58 so that in effect any "down" floor-relay switches which are in actuated position as a result of actuating their associated "down" push buttons will not be disturbed as by the engagement of the contactors 34 and 36 while direction for car movement is in an upward direction excepting in the case of any "down" floor-relay switch which controls movement of the car to a farthest-up point of dispatch. As the back-contactors 112 of the "up" direction switch are now open, the circuit for the winding 113 of the "down" direction switch is rendered inoperative and cannot close so long as the "up" direction switch is closed and in such manner any closed car start contactors 51 for landings below car position are rendered ineffective. The "up" direction switch will remain closed until the car reaches the landing farthest-up for which an "up" button is actuated or it will remain closed in response to an actuated "down" button farthest-up if it is for a landing above said landing farthest-up for which the "up" button is actuated. This is so because the floor-selector segments 38 for landings above car position are set to connect their associated wire

52 in the circuit of the "up" direction switch winding 64A, said wires 52 for each landing, as will be remembered, connecting the contactors 50 and 51 of both the "up" and "down" floor-relays 5 in parallel.

Up to the present point in the description of the operation, the car is moving upwardly at its fast speed rate, its direction of movement upwardly being originated by operation of the third 10 landing "down" button; the "up" de-energizing circuits and apparatus being rendered effective; the "down" de-energizing circuits being rendered ineffective; the stop switches on the car both in closed position and maintained in inoperative 15 or retracted position mechanically by the springs w, w' so that their rollers will not engage cams for the landings which are not stopped at, the door-lock cam in retracted position, and the "up" intercepting circuit rendered effective at 20 the contactors 7, and the "down" intercepting circuits rendered ineffective at the contactors 9. As the car moves upwardly from the first to the third landing, or for the purpose of description at this point let us say to the fourth landing, it will be caused automatically to slow down 25 and stop in response only to "up" push buttons at the landings intermediate the position of the car and the farthest-up landing for which a push button is actuated and it will be automatically slowed down and stopped at said farthest-up landing for which a push button is actuated regardless as to whether said actuated button is an "up" or a "down" button.

Slow-down of the car is effected at said landings in succession or in their natural order regardless of the order in which the push buttons are actuated, the car responding on first approach to "up" push buttons actuated prior to car arrival and on second approach in the "up" 30 direction to push buttons actuated subsequently to car arrival. Let us assume now the second landing "up" push button is actuated prior to car arrival. Pressing said button effects energization of the winding for the second landing floor-relay switch to cause the latter to close and maintain itself in actuated position through closure of its self-holding contactors to close its self-holding circuit. We now have the back contactors 61 of the "up" floor-relay switch at the 35 second landing open-circuited to open the shunt circuit around the second landing floor-selector contactors 42, 44 and 45. Hence, when the car actuates the second landing selector switch segment 42 to momentarily open-circuit contactors 44 and 45, the series energizing circuit 5' for the winding 6 is open-circuited and as the second landing shunt circuit is already open, this causes de-energization of the winding 6 to cause operation of the switch B to open-circuit its contactors 64 and 65 and close-circuit its back-contactors 66. Opening of contactors 65 de-energizes the fast and slow speed switch winding 68 to cause automatic slow-down due to the closing of the switch J to short-circuit the shunt-field resistor 50 70 75 80 85 relay switch 22. In this manner the second landing floor-relay switch is permitted to return to normal position. As soon as the car is started, the back contactors 123 of the "up" reversing switch will be opened to cause de-energization of the second landing winding 31 to permit its contactors 27 to close and thus condition the circuit for the winding of the second landing floor-relay switch so that it will be completed by actuation of the "up" push button at any time after the car has started away from its landing in either direction. The completed energizing circuit for the second landing winding 31 may be traced as follows: from a plus wire 124, back contactors 56 of the switch D', wire 55, to second landing contactor 33, contactor 35, wire 125, through winding 31, wire 126 to a common return wire 106A which connects with the minus main and includes the two sets of back contactors 123 in series of the reversing switches R, R'.

The winding 114 of the time-limit relay is de-energized by opening of the "up" reversing switch contactors 119 and thus closure of the contactors 100 and 97 is initiated at such time. By adjustment of the dash pot 99 which retards the closure of the contactors 100 and 97, a reasonable stopping period is provided to permit passengers to get off of and onto the car platform. At the expiration of such period these contactors close and initiate start of the car provided all doors and the car gate are closed, and regardless as to whether either had first been opened which in effect means that for each car stop it is not necessary in order to render the system again operable to re-start the car, that the car gate or hoistway door be first opened which operation, of course, is not effected as when a hall passenger dispatches the car but does not use it, or a car passenger delays in opening the car gate. Hence, since we already have the energizing circuit 5' for the winding 6 closed up to the contactors 100, the closing of the latter, completes the energizing circuit for the winding 6 and the switch B will close its contactors 64 and 65 and open its back contactors 66. The contactors 97 close to complete the circuit for the winding 13 of the door-lock cam. With all the hoistway doors closed and locked, the car gate if not already closed, will be unlatched by energization of the winding 19 and closed by the action of the gate-closing spring 16.

Since the energizing circuit for the "up" direction switch winding is maintained by the "down" floor relay switch contactors 51, etc. for the third landing during the stop of the car at the second landing, this "up" direction switch will remain closed during such intermediate stop at the second landing. Hence, the original direction for car movement is maintained so that with the initial energizing circuit for the "up" reversing switch winding 2 again closed at the contactors 64, the closing of the car gate contactors and the contactors 84 will complete the energizing circuit for winding 2 and in such manner, the "up" reversing switch is caused to close to continue movement of the car upwardly or in the original direction in which it was traveling as when intercepted, and the fast and slow speed switch will operate in sequence as hereinbefore mentioned to cause movement of the car at fast speed rate.

Since movement of the car upwardly to the farthest-up landing for which a button is actuated, is under the control of a "down" push button, 75 which condition is assumed in the present in-

stance, the slow-down of the car at such landing is effected by opening the "up" direction switch by de-energization of its winding at the third landing floor-selector contactors 38, 40, 42 which are timed to be open-circuited when the slow-down point is reached in the same manner as are the contactors 42, 44 and 45. Since the third landing contactors 51 and associated floor-selector contactors 37, 38 and 39 are the final feed for the "up" direction switch winding, or in other words constitute the farthest-up feed therefor, said winding will be de-energized to open its contactors 1, 7 and 101 and close its back contactors 58 and 112, when the car actuates the floor-selector switch at the third landing to open circuit contactors 38 and 39.

The opening of contactors 7 results in opening at that point the energizing circuit for the winding 6 which in effect causes automatic slow-down of the car at said farthest-up landing for which a push button is actuated. It will be particularly pointed out here that when the car is moving upwardly and a "down" push button through its control of the "up" direction switch controls its movement to a farthest-up landing for which a button is actuated, the "up" intercepting wire 5' as controlled by the floor-selector switch for the third landing cannot be depended upon to effect automatic slow-down at such point because the shunt circuit around said floor-selector switch is closed at contactors 61 and hence under such condition, the "up" direction switch is utilized to effect automatic slow-down by open-circuiting the wire 5 at contactors 7. Since for upward movement of the car, the "up" direction switch is maintained closed uninterruptedly or regardless of the number of intermediate stops until the farthest-up point of dispatch is reached, the slow-down operation through the agency of said switch is effected by a "down" push button only at said farthest point and only when the "down" button corresponds to a landing above the farthest-up landing for which an "up" button is actuated. Hence, during said upward movement of the car it will not be responsive to actuated "down" buttons for landings below said farthest point of dispatch because the "down" intercepting circuits 8 and 8', etc. are open-circuited or rendered inoperative at the contactors 9 of the "down" direction switch.

Opening of contactors 1 by the direction switch opens at that point the initial energizing circuit for the winding 2 of the "up" reversing switch but the circuit for said winding is now maintained by way of its self-holding circuit which is independent of said contactors 1 and is controlled by the contactors of the stopping switches S and S' in series. Closure of the contactors 66 results in energization of the windings 114 and 115 in series and the latter will actuate its switch S with its contactors in closed position so that the roller is in operative or cam engaging position. Hence, by co-action of the roller and cams, the stop switch is momentarily actuated to open its contactors to effect car stop, etc.

When the "up" direction switch opens, it breaks at its contactors 101 the energizing circuit for the windings 13 and 19. However, under such condition the circuit 94 therefor is maintained by feeding it from contactors 127 controlled by the reversing switch as they connect it with wire 94 by way of a wire 128. More essentially, the effect of maintaining circuit 94 is to prevent de-energization of the winding 19 to open contactors 84 when slow-down is effected 7

as in this case by a direction switch since said contactors 64 are in the circuit of the reversing switch windings and must not be opened until stop is effected.

5 We now have the car at rest at the third landing or, in other words, the farthest-up landing for which a button was pressed.

Both direction switches are now in open position and under such condition any floor-relay switch for a landing below car position, which is in actuated position will initiate movement of the car downwardly regardless of whether such actuated switch is an "up" or a "down" switch. This is so because each segment 38 below car position connects both its "up" and "down" parallel connected car start contactors 50 and 51 in the circuit of the "down" direction switch winding 113. Hence, the closing of contactors 50 or 51 of any of such floor-relay switches effects energization of the "down" direction switch so that in effect the car upon completing its "up" trip to a farthest-up landing for which a button is actuated will at the expiration of the stop period as controlled by the time-limit switch 98, and provided all hoistway doors are closed and also the car gate (which if not already closed will be automatically closed by closing the hoistway door), be caused to reverse its movement and travel downwardly. Such "down" direction switch will be maintained closed uninterruptedly regardless of the number of "down" stops until the car completes its trip to a landing farthest down for which either an "up" or a "down" button is actuated.

35 Let us assume that the button at the first landing is actuated, say, for example, at a time when the car is making its upward trip in response to the third landing "down" button. Actuation of said first landing button effects actuation of its associated floor-switch to close its top contactor and open its bottom contactors 61. Since the wire 54 is open at the back-contactors 112 when movement of the car is upwardly such closure of said floor-switch at such time is ineffective to influence the "down" direction switch. However, when the "up" direction switch closes its back-contactors 112, they together with the first landing floor-relay switch contactors 51 and the floor-selector contactors 38, 39 and 41 for said landing complete an energizing circuit for the "down" direction switch. Now when the time-limit switch again closes, the switch B is closed to initiate start of the car downwardly and effect operation thereof at its fast speed rate. The car when moving downwardly can be automatically slowed down and stopped only in response to actuated "down" push buttons in a manner effected by the "down" set of intercepting circuits consisting of the wires 8 and 8' and their associated shunts, and the stop switch S'. Of course, as hereinbefore mentioned, if a farthest-down actuated "up" button for a landing below the farthest-down landing for which a "down" button is actuated, it will bring the car to its landing and effect automatic slow-down and stop thereat by opening the "down" direction switch. For movement of the car downwardly the "up" start circuits as controlled by the contactors 50 are rendered inoperative by reason of their common return wire 53 being open-circuited at the back-contactors 81 of the "down" direction switch, and the "up" set of intercepting circuits 5, 5' etc. are rendered inoperative by reason of the wire 5 being open-circuited at the contactors 7 of the switch D. The

"down" de-energizing apparatus and circuits are rendered effective by reason of the feed wire 111 being closed at the back-contactors 58 of the switch D, and the similar apparatus and circuits for "up" direction are rendered ineffective by reason of the feed wire 55 being open-circuited at the back-contactors 56 of the switch D'.

From the description already given, it will be seen that any "up" or "down" push button actuated after the car has moved downwardly from its landing, will condition the system to initiate movement of the car upwardly when the car completes its downward trip. With the car moving upwardly to a farthest point of dispatch only "up" push buttons are effective to intercept it at landings intermediate car position and such farthest point regardless of whether the actuated buttons therefor are "up" or "down" buttons and the car is automatically slowed down and stopped at said farthest point by either the "up" or "down" button therefor.

Any "up" or "down" push button actuated after the car has moved upwardly from its landing, will condition the system to initiate movement of the car downwardly when the car completes its upward trip. With the car moving downwardly to a farthest point of dispatch only "down" push buttons are effective to intercept it at landings intermediate car position and such farthest point regardless of whether the actuated button therefor is an "up" or "down" button and the car is brought to said point and stopped thereat by either the "up" or "down" push button.

If a "down" push button is the initiating button for movement of the car upwardly it will stop the car at its landing on first upward approach of the car thereto if a button for a landing farther up is not actuated prior to the car reaching said landing. This is so because the "up" direction switch is under control of a "down" button, and under such condition opening of said direction switch is depended upon to initiate slow-down and stop at the farthest point of dispatch and, hence, said switch will open to effect stop at the landing corresponding to said "down" button if the latter constitutes the farthest-up feed for the winding of said direction switch. However, actuation of any button for a landing above the one corresponding to said "down" button, will in effect provide a feed for said winding which maintains the direction switch closed so that the car on its first approach to the landing corresponding to said "down" button will not stop thereat. However, by the single actuation of said "down" button, it will be effective when the car completes its upward trip, to initiate movement of the car downwardly and stop it thereat on such return or reverse trip of the car.

If an "up" push button is the initiating button for movement of the car downwardly, it will stop the car at its landing on first downward approach of the car thereto if a button for a landing farther down is not actuated prior to the car reaching said first-named landing. This is so because the "down" direction switch is under control of an "up" button and under such condition, opening of said switch is depended upon to initiate slow-down and stop and hence said switch will open to effect such result at the landing corresponding to said "up" button if the latter constitutes the farthest-down feed for the winding of the "down" direction switch. However, actuation of any button for a landing be-

low the one corresponding to said "up" button will in effect provide a feed farther down for said winding which maintains the direction switch closed so that the car on first approach to the 5 landing corresponding to said "up" button will not stop thereat. However, by the single actuation of said "up" button it will be effective when the car completes its downward trip to initiate movement of the car upwardly and stop it thereat 10 on such upward or return trip of the car.

The car push button and the hall push buttons which correspond as to landings and to direction, are connected in parallel so that the car push buttons will in effect control the car 15 in the same manner as do hall buttons. Hence, in view of the detailed description already given for hall button operation, a detailed description for car button operation is thought unnecessary other than to point out that the car passengers 20 need only to press the car buttons of the "up" or "down" banks in accordance with the direction in which it is desired to travel and for the landing to which travel is desired and the control 25 elements will have a mode of operation the same as described for the hall button operation. For the same reason it has not been thought necessary to encumber the drawings with a complete diagram of the connections from the car buttons. As these are in parallel with those from the hall buttons, their inclusion would be mere duplication which would tend to confusion rather than clarification of the drawings.

Provision is made for returning the car repeatedly to a predetermined landing or "home" 30 station automatically, or without necessitating actuation of any push button. To effect such result in a manner so that any landing may be selected as a "home" station, a knife-switch 125A is provided for each desired landing, said switches 35 located for manual operation at any convenient point and each switch for each intermediate landing by-passing the buttons therefor and feeding both floor-relay switch windings 24 in parallel by way of a wire 126A and parallel wires 40 127A.

The knife-switches are normally in open position so that by closing one corresponding to a landing selected as the "home" station, the energizing circuit for the two windings 24 corresponding to said station will be completed independently of the push buttons for said station. In effect then the two floor-relay switches 22 and 23 for the "home" station will be maintained closed so long as the switch 125A remains in closed 50 position excepting as each is opened only in accordance with the direction of car movement by operation of the de-energizing apparatus when the car is at said "home" station, and the one so opened being again automatically closed as the 55 car moves away from the station. Hence, by so maintaining the two floor-relay switches closed for the "home" station, the car will be repeatedly returned thereto automatically or independently of button operation, after completing its 60 trip to the farthest-up and farthest-down points of dispatch and stopped at said "home" station on approach from either direction.

Since the knife-switches 125A all control circuits of a similar nature only two are illustrated herein, one for the third landing and the other for the first landing, the latter, of course, since it is for an end landing, controlling only the one floor-relay switch therefor. It will be evident that with the knife-switches closed for all land- 75 ings, the car will be caused to travel repeatedly

between the end landings and make all stops when traveling in either direction, and the car will not be stalled for failure to open the door at any landing stopped at, because of the provision of the time-limit switch.

5

For car switch operation, the car switch G is provided. For convenience this is illustrated away from the car. It has "up" and "down" contactors 128A and 129A respectively and also speed control contactors 130 in parallel adapted for coaction 10 with a car switch segment 131 normally maintained in neutral or "off" position by a usual type of interlock for the car switch lever such, for example, as is illustrated at 132. The segment 131 is mounted so that its center of gravity is 15 above the pivotal supporting point so that when it is in "on" or running position, the operator can release the lever and the segment will be maintained in actuated position by gravity. An interlock such as 132 is preferably provided to 20 lock the car switch lever in either of its "on" positions.

For car switch control, the change-over knife-switch H is thrown from its position as illustrated to engage lower contactors 133. This open-circuits the wires 53 and 54 in the circuits of direction switch windings 64A and 113 respectively and this makes the car start and dispatch function by the car and hall push buttons inoperative. The energizing circuit for the winding 68 of the 25 switch J is also conditioned to be subject to the control of the car switch as well as to the control of the automatic speed change switch B, and the self-holding circuit for the reversing switch 30 windings is also conditioned for control by the car switch. In this manner the car starting or dispatching function is transferred to the car switch so that operation of the segment 131 to 35 close-circuit contactors 129' and 128A, closes an energizing circuit for the winding 113 of the 40 "down" direction switch to effect movement of the car downwardly. Operation of the segment 131 to close-circuit contactors 129' and 128A 45 closes an energizing circuit for the winding 64A of the "up" direction switch to effect movement of the car upwardly. Whichever direction switch is closed, functions in the same manner as heretofore described to establish and maintain direction for car movement so long as the car switch remains in "on" position, and also renders either 50 the "up" or "down" car and hall push buttons effective to intercept the car, and makes the de-energizing apparatus for the floor-relay switches effective. As hereinbefore pointed out, the dispatch or car start operation as controlled by said 55 buttons through their control of the direction switches is rendered inoperative. Hence, for car switch operation said car and hall push buttons function only to intercept the car by effecting automatic slow-down and stops but direction for 60 car movement through control of said direction switches is under control of the car switch.

With the present arrangement the car operator needs only to move the car switch lever to set the segment at will to effect movement of the 65 car at slow or fast speed in a desired direction.

The operator can then release the actuating lever to permit the segment to be maintained in actuated position by the action of gravity during an entire trip in any one direction regardless of 7 intermediate stops and until it is desired to reverse movement of the car. Hence, each start of the car from a landing at which it is intercepted is effected automatically by operation of the time- 75 limit switch or by closing the hoistway door and

car gate if they should be in open position after closure of said time-limit switch. The car operator simply actuates the car push buttons in accordance with the calls given by the car passengers, and automatic slow-down and stop in response to actuated car buttons and also in response to actuated hall buttons is effected in the same manner as hereinbefore described.

Through the intermediary of the car switch control of the direction switches, the reversing switches can be controlled to start, stop and reverse the car at will at any point intermediate the limits of car movement. Since the fast and slow speed winding 68 is fed by way of the car switch contactors 130 and the contactors 65 of the switch B in series, the fast speed and slow-down operation can be effected manually by car switch operation. Or the car switch can remain in fast speed position so that slow-down and stop is effected automatically by the opening of switch B in response to actuated car and hall push buttons.

With the change-over switch thrown over as suggested, a car switch controlled circuit, say for example for the winding 64A of the "up" direction switch, may be traced as follows: from a plus wire 134 through car switch contactors to wire 135, through change-over switch to wire 138, thence through winding 64A and from there on to the minus main as heretofore traced.

A circuit for the winding 68 of the fast and slow speed switch J may be traced as follows: wire 134 through fast speed contactor 130 to wire 137 by way of the segment 131 and feed contactor 129', through change-over switch to wire 138, contactors 65 of the switch B, wire 107, contactors 67, wire 108, winding 68 and thence to the minus main by wire 109.

With the switch H thrown over to its lower position, the self-holding circuit for the reversing switch windings as controlled by wire 104 is open-circuited at the contactors 106 and transferred to the car switch contactors 106'. Hence, rendering said self-holding circuit inoperative at the contactors 106 and subjecting it to control of the car switch, means in effect that car stop at any point can be effected by centering the car switch to open-circuit said self-holding circuit so that opening of a direction switch will de-energize the winding of the reversing switch. Or by leaving the car switch in "on" position said self-holding circuit is opened automatically by the stop switches to effect car stops in response to car and hall push buttons in the same way as hereinbefore pointed out.

By the provision of a knife-switch 158 to be located in the car (but shown elsewhere for convenience), the car can be caused to operate as express and will be non-responsive to actuated push buttons but will be subject to control by the car switch exclusively to control its starts and stops. The knife-switch 158 in the position as shown is in the intercepting energizing circuit of the winding 6 so that the switch B is subject to the control of the push buttons. However, by throwing the switch to engage contactor 159, the winding 6 is thereby rendered non-responsive to the push buttons, and is placed directly across the line so that the switch B will remain closed so long as the knife-switch engages contactors 159. Slow-down, stop and start is then controlled exclusively by the car switch. This arrangement is desirable more particularly for the reason that if the car is loaded to capacity, over-crowding the car with accompanying loss of time

is eliminated by so rendering the system non-responsive to the push buttons, but the operator having exclusive control of the car, can let any car passengers off at any desired points of operation of the car switch.

A single push button intercepting system for a multi-speed elevator as illustrated in Fig. 2 comprises one push button 146 located at each landing and one for each landing designated 146' located on the car. These car and hall push buttons which correspond as to floors are connected in parallel to control their associated floor-relay switches 147. There is only one floor-relay switch for each landing. For intermediate landings each switch is provided with two sets of back-contactors 61, 61' which together with the floor-selectors 148 control the intercepting slow-down operation of the car through control of the two sets of intercepting wires 5, 5' and 8, 8' for movement of the car upwardly and downwardly respectively through the agency of the fast and slow speed switch whose winding 6 only is shown. The floor-selectors 148 are of the same construction as in Figs. 1A and 1B and have a mode of operation the same as described for Figs. 1A and 1B, to control their respective circuits. However, for the single push button arrangement, only a single set of de-energizing mechanism is provided, comprising for each landing a movable contactor 149 and its coating contactor 150 together with a de-energizing relay 162. The contactors 149 are in parallel and are fed directly from the plus main by wire 156. The contactors 150 are connected in parallel by a common return wire 151 which after passing through reversing switch back-contactors 123, connects with the minus main by wire 157. The "up" and "down" intercepting wires 5' and 8' are controlled by the "up" and "down" direction switch contactors 1 and 9, as in Fig. 1A.

Only that portion of the system which involves changes over the Figs. 1A and 1B two button arrangement has been illustrated in Fig. 2, the circuits and apparatus not illustrated in the Fig. 2 arrangement being the same as in Figs. 1A and 1B.

According to the mode of operation of the Fig. 2 arrangement the push buttons are actuatable at any time regardless of the position of the car and the direction of car movement to effect actuation of their associated floor-relay switches to open their intercepting contactors and close their two sets of top contactors 152 and 153, the former to feed circuits 154 for the direction switch windings in accordance with car position as determined by the position of the floor-selector segments 33, and the latter to control the self-holding circuits.

During movement of the car upwardly, it will respond to any actuated push buttons for landings toward which it is moving and will respond to a farther-up actuated push button before reversal of car movement is effective. For downward movement of the car it will respond to any actuated push button for landings toward which it is moving and will respond to a farthest-down actuated push button before reversal of car movement is effective.

Of course, as will be evident the single push button arrangement does not offer hall passengers any selection in the matter of intercepting the car only when it is going in the desired direction as does the two button arrangement. The single button arrangement is considered satisfactory where inter-floor travel is infrequent, but for the

class of service where inter-floor travel is frequent, the single button arrangement through its lack of selection would promote confusion and congestion in the car, whereas the two button arrangement because of it affording selection to the hall passengers effectually prevents such conditions by segregation of "up" and "down" going hall passengers.

In the Fig. 4 arrangement the series and shunt system of circuits is retained to intercept the car by effecting automatic slow-down as in the arrangement shown in Figs. 1A and 1B. But the mechanism to control the circuits, consisting of car controlled apparatus as a whole designated by 162A together with "up" and "down" floor-relay switches designated by 163 and 164 respectively for each intermediate landing, are of a substantially different construction with a substantially different mode of operation as compared with 20 the corresponding elements of the arrangement shown in Figs. 1A and 1B, but the results so far as control of the car is concerned, are the same in both cases.

Each floor-relay switch is of a type employing 25 a trip winding 165 which by being energized momentarily in response to momentary actuation of its associated push button, moves an interlocking arm 166 from engagement with a pivoted switch in the form of a bell-crank 167 so that the latter operates through the action of 30 gravity, or a spring (not shown) to open normally closed contactors 168 to control an intercepting shunt circuit and closes normally open contactors 169 to control a car start circuit through control of "up" and "down" direction 35 switches in the same manner as do the corresponding contactors in the Figs. 1A and 1B arrangement. The floor-relay switch arm, it will thus be seen, is maintained in actuated or set 40 position mechanically as contra-distinguished from the Figs. 1A and 1B arrangement in which each floor-relay switch is maintained in actuated position electrically through the intermediary of a self-holding winding and circuit, said winding 45 serving to initially actuate or set the switch in response to momentary actuation of its associated button in addition to maintaining it in said actuated or set position. A winding 170 operates when energized as, for example, when its associated 50 switch effects stop of the car, to re-set or, in other words, rock its switch arm to an inoperative or normal position in which it is maintained by the interlocking arm 166.

The car-controlled mechanism to control the 55 "up" and "down" intercepting circuits is of a type remote from the car and comprises for each intermediate landing normally closed contactors 171 and 172 carried by pivoted switch arms 173, 173' respectively, the contactors 171 being connected in series and controllable to intercept the car when it is traveling upwardly, and the contactors 172 connected in series and controllable to intercept the car when it is moving downwardly. The "up" and "down" switches are provided 60 with rollers 174, 174' respectively, those forming the "up" set being adapted for engagement by a cam 175 and those forming the "down" set being adapted for engagement by a cam 176. The cams are movable together axially on a worm 177 rotatable by movement of the car through a cable and drum connection 178. By coaction of the cams with the switch rollers, the switches are opened only momentarily and are again re-closed, which results are obtained by the directly actuated hoistway type of switches illustrated in Fig. 75

1B, and the other modified remote type of floor-controller or selector illustrated in Fig. 3.

A standard and well known type of remote control mechanism 179 may be coupled with the worm for actuation therewith in accordance with the movement of the car. This mechanism together with the floor-relay contactors 169 function to control the direction switches.

The "up" and "down" car start contactors 163 for each floor are connected in parallel and the 1 common wires 180 leading from each set connect the two sets of corresponding contactors such as 164 and 164' at the remote controller 179 in parallel by a wire 180' so that in effect the car can be brought to the landing from either direction by 1 pressing either the "up" or "down" push button thereof.

Circuit-controlling mechanism to control the energizing circuits for the re-set magnets 178 of the floor-relay switches is of the normally open-circuited type and consists of the "up" and "down" sets of fixed contactors 182 and 183 respectively adapted for engagement by "up" and "down" contactors 184 and 185 respectively movable with the axially movable cams. 2

By extending a common return wire 186 which connects with the contactor 184, through back contactors 187 of the "down" direction switch, and extending the common return wire 187' which connects with the contactor 185, through back 3 contactors 188 of the "up" direction switch, and then extending a wire 189 connecting both sets of back contactors in parallel, through back contactors 190 and 191 in series of the "up" and "down" reversing switches, the effect will be such 3 that only "up" floor-relay switches for landings stopped at will be re-set when movement of the car is upwardly and only "down" floor-relay switches for landings stopped at will be re-set when movement of the car is downwardly, and 4 when the car reaches a farthest point of dispatch in either direction, either one or both of the floor-relay switches corresponding thereto will be re-set.

The modified construction of the intercepting control mechanism 162A and the floor-relay switch mechanism 163 and 164 does not necessitate any change to the system of electrical circuits as illustrated in Figs. 1A and 1B, for effecting the intercepting operation and to control start of the car by push button operation, and hence in Fig. 4 only such portion of said circuits is embodied therein as is thought necessary in order that the modified elements can be readily identified in association with their particular circuits. The intercepting and car start circuits are unchanged; hence, a detailed description thereof is thought to be unnecessary. With regard to the mode of operation of the floor-relay switches, it is sufficient to state that any of them are actuatable to be set in response to momentary actuation of their associated push buttons by energization of their associated trip magnets at any time regardless of the position of the car and the direction of car movement at the time they are actuated.

The re-set magnet for any particular floor-relay switch which effects stop of the car is energized by way of a wire 192 which connects with a plus main; thence through the re-set magnet of the "up" or "down" floor-relay switch which stopped the car (and for the sake of illustration, it will be assumed that the "up" floor-relay switch 193 which corresponds to the third landing is the one to effect the stop) wire 194, contactor 182 for said landing to movable contactor

184, wire 186, back contactors 187 of the "down" direction switch, and thence by wire 189 to the minus line by way of the back contactors 190 and 191 of the reversing switches.

- 5 Referring back to the arrangement illustrated in Figs. 1A and 1B, it will be particularly noted that when "up" car movement to a farthest-up point of dispatch is under control of a "down" push button, or to be more specific, its associated "down" floor-relay switch, the latter will be returned to normal position or if both floor-relay switches for such point are in actuated position, both will be returned to normal position. Likewise when "down" car movement to a farthest-down point of dispatch is under control of an "up" button or "up" floor-relay switch, the latter will be returned to normal position, or if both floor-relay switches for such point are in actuated position, both will be returned to normal position. This is so because with the car stopped at either of said farthest points both direction switches are in open position and close their back-contactors 58 and 56 to close both feeds 111 and 55 for the de-energizing windings 31 and 32 respectively and both the "up" and "down" sets of contactors 33 and 35, and 34 and 36 respectively are in engagement. In such manner the energizing circuits for both windings 31 and 32 are completed and both sets of contactors 27 and 29 will thus be opened to effect return to normal positions of whichever one of the floor-relays is in actuated position, or both if both are in actuated position.

By including the circuit for the "up" direction switch winding through back-contactors 195 of the "down" reversing switch, and including the circuit for the "down" direction switch winding through back-contactors 196 of the "up" reversing switch, and by providing each direction switch with a dash pot 197, a direction switch cannot start its closing movement in response to an actuated button to condition the system for reverse car movement until stop of the car is effected, and then by retarding such closing movement of a direction switch and arranging one of the back-contactors of each direction switch to have a short follow-up movement, said contactors 58 and 56 together with their associated circuits, etc., will thus be given sufficient time to function to return the floor-relay or relays for such farthest point of dispatch, to normal position before final closure of such direction switch, which final closure of the latter will, of course, open-circuit its back-contactors.

55 This invention in its embodiments as either a two button or single button arrangement for a multi-speed elevator is an improvement on co-pending applications, one by the applicant, Serial No. 127,522, filed August 6, 1926, now Patent 1,983,748, and one by Carl Erickson, Serial No. 146,609, filed November 6, 1926, both of said inventions and the present one also, assigned to the Gurney Elevator Company. In said co-pending applications only the hall push buttons at landings toward which the car is moving are effective to actuate their floor-relay switches which means that the push buttons at landings which the car is moving away from if actuated at such time would be ineffective, that is, they would not set their floor-relay switches so that in effect such buttons would need to be actuated a number of times, whereas in the present application any of the push buttons are actuatable at any time and need to be actuated only once in order to effect response of the car thereto. In the present

case, car switch control of the car does not interfere with the setting of any of the push buttons, whereas in said Patent 1,983,748, reversal of the car by car switch operation will in effect open any actuated floor-relays for landings toward which the car travels.

Furthermore, the present two button arrangement is a distinct improvement on a single button arrangement for reasons hereinbefore mentioned.

What I claim is:

1. A control system for an elevator car comprising control means at each of a plurality of landings for controlling both starts and stops of the car, car carried means for controlling car starts and stops, and means for rendering either the car carried or the landing car start control means effective to the exclusion of the other, and retaining the car stop function of both landing and car carried controls when the car start function of the landing controls is rendered ineffective. 10
2. A control system for an elevator car comprising control means on the car operable at will to stop movement of the car and cause reverse movement thereof, and means for each of a plurality of landings to cause both start and stop 25 of the car, and means to condition said landing control means to control only car stops while simultaneously rendering the car carried control means effective to start the car, any of said landing control means at the landings requiring actuation only once to effect response thereto regardless of the direction of car movement when actuated. 30

3. A control system for an elevator car comprising a plurality of control means at each of a plurality of landings, any of said control means actuatable at any time regardless of car position and direction of car movement, a circuit for each control means effective to maintain same in actuated position, and means responsive to stopping 40 of the car, the direction of travel of the car prior to stopping, and the position of the car with respect to a floor landing, only, effective to return to normal position only such actuated control means as cause the stop of the car without affecting other actuated control means. 45

4. A control means for an elevator car comprising control instrumentalities therefor at each of a plurality of landings, each control including a winding and an energizing circuit therefor, car stopping means rendered effective by energization of any of said windings, normally closed contactors in each of said circuits, and means responsive to direction of car travel, and the position of the car with respect to a floor landing 55 effective to deenergize the winding only if and when the car stops at the landing with which said contactors are associated and in response to energization of said winding.

5. A control means for an elevator car comprising a floor relay having a winding, a circuit therefor, said winding being energizable at any time regardless of car position and direction of car movement, car stop means controlled by said relay, means for maintaining said winding energized until said relay effects car stop, and means for deenergizing said winding when the car stops in response to operation of the car stop means acting under the influence of said relay, said deenergizing means for the relay winding being 70 responsive to stopping of the car, the direction of travel of the car prior to stopping, and the position of the car with respect to a floor landing, only. 75

6. A control system for an elevator car com-

prising "up" and "down" controls at each of a plurality of landings to control the car, any of said controls actuatable at any time and maintained in actuated position electrically until response is made thereto, a de-energizing winding for each of said controls, a feed circuit common only to "up" de-energizing windings, a feed circuit common only to "down" de-energizing windings, supply mains, means to condition only said "up" feed circuit for connection to said supply mains when movement of the car is upwardly, means to condition only said "down" feed circuit for connection to said supply mains when movement of the car is downwardly, means responsive to stopping of the car, the direction of travel of the car prior to stopping, and the position of the car with respect to a floor landing, only, for selectively connecting the "up" and "down" deenergizing windings of actuated floor landing controls to said supply mains.

7. An intercepting push button control system comprising a floor relay switch having a winding and an energizing circuit therefor opened only when the car is at the landing corresponding to said switch whereby said switch is maintained closed to cause return movement of the car to its landing repeatedly independently of manual operation.

8. An intercepting circuit comprising a car actuated switch for each of a plurality of landings, said switches being connected in series and said series circuit being completed through all of said car actuated switches when the car is at any landing, and a shunt around each of said switches operable to be opened at any time regardless of the position of the car and the direction of car movement.

9. An intercepting circuit comprising a car-controlled switch for each of a plurality of landings, connected in series, a shunt around each of said switches, and electrical means controllable manually to control said shunts selectively at any time regardless of the position of the car and the direction of movement of the car.

10. An intercepting circuit comprising contactors for each of a plurality of landings forming a series circuit which is opened by the car only momentarily as it approaches each landing and is re-closed by the car so that with the latter at any landing, said series circuit is completed by way of all of said contactors.

11. An intercepting circuit comprising car actuated switch mechanism for each of a plurality of landings, said mechanisms together forming a series circuit, a shunt circuit around said switch mechanism for each landing, and a winding controllable by said series and shunt circuits, so that start of the car from each landing stopped at is effective by energization of said winding by said series circuit independently of said shunt circuits.

12. An intercepting circuit comprising car actuated switch mechanism for each of a plurality of landings, said mechanisms together forming a series circuit, a shunt circuit around said switch mechanism for each landing, a winding controllable by said series and shunt circuits so that start of the car from each landing stopped at is effective by energization of said winding by said series circuit independently of said shunt circuits, and a time-limit switch in said series circuit.

13. A control system for an elevator car comprising a control for each of a plurality of landings, a car switch effective to start and stop the car at will, said controls effective with the car

switch in "on" position to intercept the car at their landings, and means to render said controls ineffective so that the car switch operates exclusively to control the car without rendering said controls non-actuable.

5

14. A control system for an elevator car comprising a control for each of a plurality of landings, said controls having combined dispatch and intercepting functions, and means to condition said controls to be effective only to intercept the car, or to be ineffective with respect to both their dispatch or intercepting functions without rendering said controls non-actuable.

10

15. In combination, an elevator car, a car gate, hoistway doors and contactors controlled thereby, and means operable automatically to cause closure of the gate only when all of said hoistway door contactors are closed.

15

16. In combination, an elevator car, a car gate having a closer therefor, a device to maintain 20 said gate in open position against the action of said gate closer, an electro-responsive device operatively associated with said maintaining device, and a time-limit switch effective at the expiration of a predetermined period of time after each 25 stop of the car, to energize said electro-responsive device to control said maintaining means so that the gate closer is rendered effective to close said car gate, and automatically to start the car.

20

17. In an elevator system, an elevator operable 30 past a plurality of floors, a closure for said elevator, means biasing said closure to closed position, means operable when said closure is opened for maintaining said closure open against the effect of said bias, and means operably responsive to the position of said elevator for rendering said maintaining means effective only when said elevator is adjacent to any one of said floors.

30

18. In an elevator system, an elevator operable 40 past a plurality of floors, a closure for said elevator, means biasing said closure to closed position, means operable when said closure is opened for maintaining said closure open against the effect of said bias, and means operably responsive to the position of said elevator for rendering 45 said maintaining means effective only when said elevator is substantially level with any one of said floors.

40

19. In an elevator system, an elevator operable 50 in a hatchway past a plurality of floors, a gate for said car, a closure for said hatchway at each of said floors, means biasing said gate to closed position, means for holding said gate in open position when so moved, means for releasing said holding means, and means operable by movement 5. of any of said hatchway closures for preventing actuation of said releasing means while said closure is open.

50

20. A control means for an elevator car comprising a floor relay having a winding, a circuit 6 therefor, said winding being energizable at any time regardless of car position and direction of car movement, car stop means controlled in part by said relay, car operated means also controlling said car stop means, and means responsive to 6 direction of car travel and actuation of said car operated means for deenergizing said winding, rendered effective to reset said relay only when the car stops at said landing in response to operation of the car stop means acting under the influence of said relay.

6

21. In combination, an elevator car, a car gate manually movable to open position, means for holding the door in open position when so moved, a closer for the door, contactors controlled by the 7

7

- door, a car start circuit including said contactors and a time-limit switch effective at the expiration of a predetermined period of time after the car stops to release said door holding means and cause 5 said closer to close said gate, thereby to close said gate contactors to complete said car start circuit to start the car independently of manual operation.
22. A control system for an elevator car comprising control means for each of a plurality of landings, directional means for each of said landings, having up and down positions as governed by direction of movement of the car, said control means in conjunction with said directional means 10 effective to govern direction of car movement and cause start of the car, and said control means effective so that those actuated before the car in its approach to each landing reaches a predetermined distance therefrom, intercept the car on its 15 first arrival thereat regardless of the order in which the control means are actuated, and those actuated during approach of the car to each landing but after it has passed said predetermined distance therefrom intercept the car upon a subsequent arrival, regardless of the order in which the control means are actuated.
23. An elevator system comprising an elevator car, a plurality of controls, one for each of a plurality of landings, directional means for each of said landings having up and down positions as governed by direction of movement of the car, means responsive to actuation of any one of said control means and in conjunction with said directional means to establish direction for car movement and cause start of the car, and thereafter 20 responsive to all actuated control means for causing restart of the car after stop until stops have been made in response to all actuated control means, and means responsive to said actuated control means to cause stop of the car at their landings in the natural order of the landings regardless of the order in which said control means are actuated, said stopping means being non-responsive to any control means actuated during 25 said restart of the car from its landing but being responsive to any control means actuated at such time to stop the car thereat on a subsequent trip of the car.
24. A control system for an elevator car comprising a plurality of controls, one for each of a plurality of landings, directional means for each of said landings having up and down positions as governed by direction of movement of the car, said control means in conjunction with said directional means effective to govern direction of car movement and to cause start of the car, said control 30 means requiring actuation only once to effect response of the car thereto regardless of the position of the car and the direction of movement of the car when actuated, and effective to intercept the car at landings in their natural order regardless of the order in which the control means are actuated, the restart of the car from any landings stopped at being non-interrupted by actuation of their controls at such time, the controls by actuation at such time being effective to cause the car to respond thereto on a subsequent trip of the car.
25. A control system for an elevator car comprising a plurality of controls, one for each of a plurality of landings, a stop switch on the car and cams in the hoistway adjacent each landing, and electro-responsive means responsive to said controls to move said switch from a retractive to a non-retractive position to cooperate with said cams, said controls being actuatable at any time, 35 and means for rendering said electro-responsive means effective to move the car carried switch to a non-retractive position to intercept the car at landings in their natural order, regardless of the order in which said control means are actuated, and means to render said electro-responsive means ineffective to cause said stop switch to intercept the car at landings on first arrival thereat whose control means are actuated after the car in its approach to landings has come within a predetermined distance therefrom corresponding to the point at which the stop switch first engages said stopping cams.
26. A control system for an elevator car comprising a plurality of controls, one for each of a plurality of landings, a single stop switch and actuating cams therefor brought into and out of cooperative relation in accordance with the movement of the car, and means to move said switch to a non-retractive position to condition it for 40 actuation when brought into said cooperative relation with a cam by movement of the car, said control means being operable at any time, means effective to render said switch moving means responsive to said control means to so condition said switch to cause its operation to intercept the car at landings successively in their natural order regardless of the order in which said control means are actuated, and including means to render said switch moving said means ineffective to 45 so condition said switch to intercept the car on first arrival at landings whose control means are actuated after the car in its approach to landings has come within a predetermined distance therefrom corresponding to the point at which said stop switch and a cam engage to cause stop of the car.
27. A control system for an elevator car comprising control means for each of a plurality of landings, a car switch to control start, stop and reversal of the car at will, and means responsive to said controls to intercept the car at landings successively in their natural order while the car is running under control of the car switch and without changing the position of said car switch 50 from its running position.
28. A control system for an elevator car comprising control means at each of a plurality of landings, control means on the car for each of said landings, a car switch to control start, stop and reversal of the car at will, and means responsive to said controls both on the car and at said landings to intercept the car at landings successively in their natural order while the car switch is in running position and without changing such 55 position thereof.
29. A control system for an elevator car comprising control means for each of a plurality of landings, a manual control means on the car having up, down and neutral positions, hoisting motor mechanism for the car, having its stop controlled by positioning said means in neutral position, and its start controlled by the two other positions of said means, said control means effective while said other means is in either up or down position and without disturbing same while in said position to control said hoisting motor to effect stop of the car at landings in their natural order regardless of the order in which the control means are actuated.
30. A control system for elevators comprising in combination a car, multi-speed motive means therefor, a plurality of controls, one for each of a plurality of landings, slow-down control means for said motive means, a car switch having fast 60
- 70
- 75

speed running position to control said slow-down means, said slow-down means responsive to said first named control means to cause said motive means to slow-down successively at landings in their natural order regardless of the order in which said first named control means are actuated and without changing position of said car switch from fast speed running position.

31. A control system for an elevator comprising in combination, an elevator car, multi-speed motive means therefor, a plurality of controls one for each of a plurality of landings, slow-down control means for said motive means, a car switch having fast speed running position, said slow-down control means responsive to said car switch to cause slow-down of the car at will and at the same time responsive to said first named control means to cause said motive means to slow-down at landings in their natural order regardless of the order in which said control means are actuated.

32. A control system for an elevator comprising in combination a car, multi-speed motive means therefor, a plurality of controls one for each of a plurality of landings, slow-down control means for said motive means, a car switch to control direction of car movement and to start the car and having fast speed running position, said slow-down means responsive to said car switch to cause slow-down of the motive means at will and at the same time also responsive to said first named control means to cause said motive means to slow-down at landings in their natural order regardless of the order in which said control means are actuated.

33. A control system for an elevator comprising in combination a car, multi-speed motive means therefor, a plurality of controls one for each of a plurality of landings, slow-down control means for said motive means, a car switch to control direction of car movement and to start and stop the car at will and having fast speed running position, said slow-down means responsive to said car switch to cause slow-down of the car at will, and responsive to said first named control means to cause automatic slow-down and stop of the car at landings in their natural order, regardless of the order in which said control means are actuated.

34. A control system for an elevator car comprising in combination, a car, multi-speed motive means therefor, a plurality of controls one for each of a plurality of landings, start and stop control means together with fast and slow speed control means responsive to said first named control means, to intercept the car at landings, a car switch to control said start, stop and fast and slow-speed control means, and means effective so that said start, stop and fast and slow-speed means are responsive to said first named control means to the exclusion of said car switch, and effective also so that said start, stop and fast and slow-speed means are responsive to said first named control means only to intercept the car but not to control its starts.

35. A control system for an elevator comprising in combination, an elevator car, multi-speed motive means therefor, up and down control means at each of a plurality of landings, control means on the car for each landing, slow-down control means for said motive means, said slow-down control means responsive to said car switch to slow-down the car at will, and responsive to said control means at the landings and on the car to slow-down the car at their landings

in their natural order regardless of the order in which said control means are actuated.

36. A control system for an elevator comprising in combination, a car, multi-speed motive means therefor, up and down control means at each of a plurality of landings, control means on the car for each of said landings, slow-down control means for said motive means, a car switch to control said motive means to govern direction of car movement to cause start and stop at will and having fast speed running position, said slow-down means responsive to said car switch to slow-down the car at will and at the same time responsive to said control means on the car and at said landings to slow-down the car and cause it to stop at landings successively in their natural order regardless of the order in which said control means are actuated, up control means causing response only when the car is moving upwardly and down control means causing response only when the car is moving downwardly.

37. A control system for an elevator car comprising control means for each of a plurality of landings, a car switch, and a car starting and stopping circuit including two switches connected in series, both of said switches responsive only to said car switch to cause start of the car, and only one of said switches being responsive to said control means only to cause automatic stop of the car at landings.

38. A control system for an elevator car comprising control means for each of a plurality of landings, a car switch, hoisting motor and brake control means responsive to said first named control means to cause start and stop of the car at landings in their natural order, said first named control means requiring only a single actuation to effect response thereto regardless of the position of the car when actuated, said second named control means also responsive to said car switch to cause start of the car and means to condition said first named control means to cause only stop of the car and at the same time condition the car switch to control the start of the car.

39. A control system for an elevator car comprising control means for each of a plurality of landings, a car switch, hoisting motor and brake control means responsive to said first named control means to cause start and stop of the car at landings in their natural order, said first named control means requiring only a single actuation to effect response thereto regardless of the position of the car when actuated, said second named control means also responsive to said car switch to cause start of the car, and a change-over switch operable for one position to render said first named control means effective to control the start and stop of the car and at the same time render said car switch ineffective, and operable for another position to render said first named control means effective to control only stop of the car and at the same time render said car switch effective to control the car.

40. A control system for an elevator car comprising control means for each of a plurality of landings, a car switch, hoisting motor and brake control means responsive to said first named control means to cause start and stop of the car at landings in their natural order, said first named control means requiring only a single actuation to effect response thereto regardless of the position of the car when actuated, said second named control means also responsive to said car switch to cause start, reversal and stop of the

car at will, and means to condition said car switch to control start and reversal of the car at will to the exclusion of said first named control means and at the same time render said first named control means effective to cause only stop of the car.

41. A control system for an elevator car comprising control means for each of a plurality of landings, a car switch, and a car starting and stopping circuit including two switches connected in series, and a change-over switch operable for one position to render both of said switches responsive only to said car switch to cause start of the car while at the same time only one of said switches is responsive to said control means only to cause stop of the car at their landings, and operable for another position to render both of said switches responsive only to said control means to the exclusion of said car switch, to cause start of the car and to intercept it at their landings in their natural order regardless of the order in which said control means are actuated.

42. In combination, an elevator car, control means for each of a plurality of landings requiring only single actuation to effect response of the car thereto, a car gate, a closer for said gate, a circuit controller actuatable by said gate, and hoisting motor and brake control means responsive to said first mentioned control means to cause automatic stop of the car at their landings in their natural order regardless of the order in which they are actuated, a timing device, said gate closer being responsive to said timing device to cause closure of the gate which when in closed position actuates said circuit controller to cause said hoisting motor and brake to operate to automatically restart the car from each landing stopped at until all registered calls are answered.

43. In combination, an elevator car, control means for each of a plurality of landings requiring only single actuation to effect response thereto and effective to stop the car at their landings in their natural order regardless of the order in which they are actuated, a car gate having a closer, a circuit to cause start of the car, a gate actuated circuit controller, and a timing device to control duration of each stop of the car effective to control said gate closer automatically to cause closure of the car gate which when in closed position actuates said circuit controller to cause energization of said starting circuit to automatically cause restart of the car from each landing stopped at.

44. In combination, an elevator car, control means for each of a plurality of landings requiring only single actuation to effect response thereto, a hoist-way door at each landing and contacts controlled thereby, a car gate, a circuit controller actuatable by said gate, and hoisting motor and brake control means responsive to said control means to cause automatic stop of the car at their landings in their natural order regardless of the order in which said control means are actuated, a timing device, said gate closer being responsive to said timing device to cause closure of the gate only if said door controlled contacts are closed, said gate when closed thus actuating its said circuit controller to cause said hoisting motor and brake to operate to automatically restart the car after each stop until all registered calls are answered.

45. In an elevator system, an elevator oper-

able past a plurality of floors, a closure for said elevator, means biasing said closure to closed position, means operable when said closure is opened for maintaining said closure open against the effect of said bias, and means operably responsive to the position of said elevator for rendering said maintaining means effective only when said elevator is adjacent to any one of said floors.

46. In an elevator system, an elevator operable past a plurality of floors, a closure for said elevator, means biasing said closure to closed position, means operable when said closure is opened for maintaining said closure open against the effect of said bias, and means operably responsive to the position of said elevator for rendering said maintaining means effective only when said elevator is substantially level with any one of said floors.

47. In an elevator system, an elevator operable in a hatchway past a plurality of floors, a gate for said car, a closure for said hatchway at each of said floors, means biasing said gate to closed position, means for holding said gate in open position when so moved, means for releasing said holding means, and means operable by movement of any of said hatchway closures for preventing actuation of said releasing means while said closure is open.

48. A control system for an elevator car, comprising landing controls, a car carried control, means for selectively rendering the car carried control effective or ineffective, and means for stopping the car either by operation of the car carried control, or by operation of said landing controls when said car carried controls are rendered effective, and means whereby said landing controls are effective to stop the car with the car carried control in car running position.

49. In a push button system of elevator control, the combination of an elevator car, a hoisting motor, push button controlled circuits and apparatus for automatically effecting start and stop of the car locally, a car carried control for manually effecting start and stop of the car locally, means for rendering the car carried control effective for starting and stopping the car while rendering the push button controls effective to stop the car only, and means to effect a non-interrupted operation of the car between non-adjacent predetermined landings, when desired, under control of the car carried control and regardless of actuated push buttons.

50. In a control system for elevator cars, a car, a hoisting motor therefor, a switch controlling said motor, electro-responsive means for actuating said switch, a circuit for said electro-responsive means and including contactors, electro-responsive means to actuate said contactors, landing push buttons to which said second mentioned electro-responsive means is responsive for opening said circuit for effecting operation of the motor controlling switch to open position to stop the car, a car carried switch for effecting opening of the said motor control switch independently of said second mentioned electro-responsive means, and means to maintain said circuit intact regardless of operated push buttons to effect non-interrupted operation of the car under control of the car carried control means, between selected landings.

ERNEST L. GALE.
